(57) CLAIM

We claim the ornamental design for a soft wall tub surround, as shown and described.

DESCRIPTION

FIG. 1 is a perspective view of the soft wall tub surround.

FIG. 2 is a top view of the soft wall tub surround.

FIG. 3 is front view of the soft wall tub surround; and,

FIG. 4 is a side view of the soft wall tub surround.

The broken line showing of portions of the tub surround is for illustrative purposes only and forms no part of the claimed design.
